PORTABLE HEATER

John R. MacGregor, Albany, and Eldred E. Edwards, Oakland, Calif., assignors to Standard Oil Company of California, San Francisco, Calif., a corporation of Delaware

Application April 25, 1932, Serial No. 607,461

2 Claims. (Cl. 236—80)

This invention relates to portable heaters which may be temporarily installed in compartments, such as refrigerator cars, in which it is desired to maintain air temperatures within certain narrow limits. For example, when it is desired to transport perishable foodstuffs during sub-zero weather, it has been the practice to use refrigerator cars for this purpose. No ice is used or is necessary in the cars under these circumstances and at intervals when access may be had to the doors of the cars, portable charcoal or coke braziers are used to bring the temperature within the car above the freezing point of the produce being stored or shipped. Present heaters of this type will continue to send out heat for several hours after the supply of additional fuel has been shut off, due to the quantity of fuel which is necessary to support combustion, and which will continue to burn for a long period of time. It is well known that many foodstuffs are severely damaged not only by freezing but also by subjection to too high temperatures and the procedure outlined above has been followed in an endeavor to prevent such damage by freezing. It is well known that such intermittent and uncontrolled heating of the air within the cars does not prevent over-heating at times when the burners are in operation and under-heating or freezing when the cars are in motion and access cannot be had to their interiors for long periods of time. This invention, therefore, consists of a small and readily portable heater with a self-contained source of fuel and accurate and positive safety and control devices to insure its safe and satisfactory operation. It will be understood that this device is intended to maintain the air in a compartment, which may or may not be a refrigerator car, at a closely controlled temperature above that of a lower surrounding or ambient temperature.

The requirement for portable and temporary heaters of this type is not limited to refrigerator cars but is also found in storage sheds and the like where perishable materials, which may be damaged by low temperatures, are stored.

It is an object of this invention to provide a small, compact, and readily portable heating unit with a self-contained source of fuel and automatic means for safely and accurately regulating the temperature produced.

Another object of this invention is to provide a structure which will not be disturbed or damaged by severe shocks and jars incident to transportation in conventional railway cars.

Still another object of this invention is to pro-

vide an apparatus which will be safely operable by unskilled attendants.

Another object of this invention is to provide a space heater which is capable of maintaining a minimum temperature in the compartment in which it is located which will not vary more than two or three degrees from a given mean.

Another object is to utilize as fuel for the heater a hydrocarbon gas such as is commercially available in compressed or liquefied form.

Another object of this invention is to provide a regulating apparatus for a heater of this type which will automatically shut off all fuel supply in case the pilot burner becomes extinguished.

Another object is to provide an apparatus which is adapted to be placed in or removed from a refrigerator car or similar structure without alteration to the car structure.

Another object of this invention is to provide a heater which will maintain its adjustment regardless of changes in altitude and consequent changes in atmospheric pressure upon its control mechanism.

Another object of this invention is to provide a portable heater which is adapted to be stacked for convenience and economy in storage and transportation.

These and other objects and advantages of this invention will become apparent from the following detailed description of preferred embodiment of this invention and its manner of operation, it being understood that the invention is not limited to the arrangement specifically described.

In describing this invention reference will be made to the accompanying drawings which form a part of this specification. In these drawings Figure 1 represents a vertical and part sectional view through a heater constructed according to this invention.

Figure 2 represents a plan view of the apparatus shown in Figure 1.

Figure 3 represents a sectional detailed view of the safety shut off valve.

Figure 4 represents a vertical sectional view through one form of thermostatic pilot valve control element and diaphragm actuated valve.

Figure 5 represents a sectional view through the thermostatic pilot valve control element.

Figure 6 illustrates a plan view of an alternative form of thermostatic head for a pilot valve control member for the diaphragm actuated main valve.

Figure 7 represents a side elevation of the thermostatic head shown in Figure 6.

Figure 8 is a detailed section on line VIII—VIII of Figure 6.

Referring to Figures 1 and 2, the numeral 11 represents a flat steel plate base of the general shape shown, provided with lifting handles 12 and hold-down devices 13 and 23.

The hold-down device 13 is fixed in position on the base 11. It utilizes a metal strap 14 which straddles a hole 15 through the base. A conventional toggle bolt 16 is arranged to move longitudinally in the sleeve 17, which latter is attached to the strap 14. The bolt 16 is urged upwardly when not in use by a helical spring 18, restrained between the bottom of sleeve 17 and an adjustable wing nut 19. A cotter pin 20 through the top of bolt 16 prevents loss of the wing nut 19.

The pivoted head 21 of the toggle bolt 16 is adapted to be passed downward through the usual slotted floor grating 22 of the refrigerator car, whereupon the bolt 16 is turned through 90 degrees and released. The wing nut 19 is then screwed down on bolt 16 to seat on the top of sleeve 17, holding the base securely against the floor grating.

The other two hold-down devices 23, located at the opposite end of the base 11 are mounted to be horizontally adjustable, in order that they may accommodate various spacings of floor gratings 22, and also that they may be used in conjunction with ears or clips on the sides of a shield member, which will be described later, to hold a stack of heater units together during storage or transportation. Hold-down devices 23 on the tank end of the base 11 are only different from hold-down device 13 just described by their being mounted upon a flat bar or strip 24 which is secured to the base plate 11 by a stud 25 and nut 26 in such a manner that the hold-down devices may be moved about the stud as a center.

A pair of steel rods 27 are attached to plate 11 by threading or welding and are fitted with an angle iron cross-piece 28, which latter is drilled and cut out to fit over the neck of a liquefied hydrocarbon storage tank or bottle 29. Wing nuts 30 on the threaded upper ends of tie rods 27 serve to clamp the tank firmly against the base plate 11. A sheet steel guard or shield 39 is attached to the base 11 and extends from one tie rod 27 around the burner and control apparatus to the other tie rod 27, thus protecting these elements and preventing radiant heat from being transferred to material immediately adjacent the heater.

Three bifurcated ears or lugs 31 are mounted on shield 30 and a small supplementary shield 118 which will be described later, as shown, and are adapted to receive the heads 21 of toggle bolts 16 of the hold-down members 13 and 23, of a superposed unit during such times as the units are not in service and are stacked in tiers for storage or shipment. Base 11 is provided with arcuate cuts as shown adjacent to hold-down members 23 to allow this to be done.

At the upper end of the tank 29 and attached to the conventional valve and union outlet 32, found thereon, is a metal conduit 33, preferably of seamless copper, which may be looped, as shown, to allow for movement in connecting and disconnecting. Conduit 33 leads to a conventional pressure reducing valve 34, which is provided with the customary adjustment handle 134 and an indicating pressure gauge 35. The pressure reducing valve mechanism is mounted on top of a standpipe or header 36 which is welded or

otherwise attached to the base 11, and is securely closed or blanked off at its lower end.

In the standpipe 36 and immediately below the outlet of the pressure regulator 34 is mounted a thermostatically controlled spring actuated safety shut off valve, generally designated as 37, which is designed to shut off the gas flow from the pressure regulator in case the pilot flame, to be described below, becomes extinguished.

Referring now to Figure 3 which shows the details of safety valve 37, it will be seen that this valve may utilize a conventional globe valve body 38, fitted with a guided valve plug 39, which is normally held from its seat by a coiled spring 40. A diaphragm 41 is clamped between the valve bonnet 42 and the top of the globe valve. An adjustable plug 43 screwed into the valve plug 39 may be moved relatively to valve plug 39 so that the allowable deflection of the diaphragm 41 is not exceeded during the maximum travel of the plug 39 from its open to its closed positions.

A metal frame or bracket 44 extends axially from the valve body 38, and is fitted with a pin 45, which forms the bearing of a bell crank 46, one end of which rests on the top of the diaphragm 41. The other end of bell crank 46 terminates in a pin 47 which extends at right angles to the main body of the bell crank. A bimetal strip 48 is provided at one end with a bearing 49 which encloses pin 47. The other end of the bimetal strip 48 terminates in a hinge 50 provided with a pin 51. A metal strip 52 is provided at one end with a loop which forms the other half of the hinge 50. Strip 52 is fitted near its midpoint with a loop 53 which fits over a pin 54 at the outer extremity of the bracket 44. Strip 52 is bent, as shown, and is provided with an extension or seating handle 55.

It will be seen that bimetallic element 48 and strip 52 form two parts of a hinged toggle which is illustrated in its actuated or collapsed position. In this position it will be noted that spring 56 will move bell crank 46 to close the valve member 39 upon its seat.

Bimetallic element 48 is bent to be concave outwardly as shown and with the metal having the higher co-efficient of expansion on the concave side. Thus, when it is cold, bimetallic element 48 will press against the adjustment screw 57, making it impossible for the toggle to remain straightened unless it is held in that position by means of extension 55.

To open valve 37 and allow gas to flow therethrough, handle 55 is moved clockwise about pin 54, thus moving hinge 50 toward bracket 44 and straightening the toggle against the stop screw as just described. It is held in this position until heat from the pilot burner, to be described later, bends the bimetallic element 48 to be concave inward or toward the stop screw 57, allowing the hinge 50 to reach a point past the straightened position of the toggle. As long as heat is supplied to bimetallic element 48 the hinge 50 will remain in this position, element 48 being then concave inwardly or around the stop screw 57. If this heat should fail due to the pilot flame becoming extinguished, the bimetallic element will move the center hinge 50 of the toggle upward beyond its straightened position allowing the toggle to collapse and causing the bell crank 46 to move under the influence of its spring 56 to close the valve plug 39 against its seat. It will be noted in Figure 1 that the safety valve 37 is so mounted that heat from the pilot burner is directed against bimetallic member 48.

Referring again to Figure 1, it will be seen that immediately below valve 37 is a T connection 58 from which a tube 59, preferably of seamless copper, leads to the pilot valve control element 5 of a gas pressure actuated main valve generally designated 60.

One form of a main valve assembly 60 is shown in Figure 4 and will now be described. It consists of a conventional globe valve body 61 provided with a small diameter raised ring seat 62. A soft metal or composition valve disc 63 is adapted to seat on the ring 62, and is mounted at the lower end of a guide plug 64. The bonnet 65 of the valve is adapted to clamp over a flanged sleeve 66. Between the face of the flanged member 66 and the top of member 61 is clamped a diaphragm 67 which prevents gas leakage around the stem 68 of the guide plug 64. A recessed plate 69 is mounted on top of member 66 and forms the lower half of a main diaphragm chamber, and also a support for the pilot valve mechanism. A cover plate 70 is fastened to the top of plate 69 by means of screws or the like. Clamped between members 69 and 70 is a diaphragm 71, to which is attached the stem 68 of the gas valve by means of reinforcing members 72 and 73.

Mounted on top of plate 70 are two needle valves 74 and 75, which seat into two drilled passages 76 and 77 that, in turn, lead respectively into the spaces below and above diaphragm 71. Needle valves 74 and 75 are mounted in threaded plugs 78 and 79 respectively, which plugs are provided with small longitudinal passages 80 and 81, for a purpose which will be explained below. A threaded cap 82 normally covers the needle valves 74 and 75 and may be removed for adjustment of these valves. This cap communicates with a conduit 83 leading to the pilot burner, which will be described later.

Conduits 84 and 85 lead from the upper and lower cavities of the diaphragm chamber formed by diaphragm 71 with members 69 and 70 to orifices 86 and 87 respectively (Figure 5) of the thermostatic pilot valve mechanism. These orifices are mounted in the lower part of a tube 88, which is provided at its lower end with a slotted stop member 89 and a closure cap 90.

At the upper end of tube 88 is mounted a flange 91 on which a second flange 92 is held by means of suitable screws 93. Surrounding flanges 91 and 92 is a tubular sleeve 94 which extends upwardly. A short distance above the top of flange 92, and extending through sleeve 94 is a hinge pin 95 for the thermostatic element and pilot valve mechanism.

This mechanism consists of a rod 96 which extends from a point near the upper end of sleeve 94 downward to a point near the orifices 86 and 87. Where it passes into tube 88 it is sealed by means of a diaphragm 97, which is clamped between flanges 91 and 92. The lower end of rod 96 is slotted to receive a flat strip 98 which extends downwardly into the stop member 89 whose slotted opening limits the motion of strip 98 about the pin 95. On member 98 and directly opposite the opening of the opposed orifices 86 and 87 is mounted a soft rubber or composition valve seat 99, which is adapted to close either orifice 86 or 87, depending upon which way the rod 96 is moved about the hinge pin 95.

Attached to rod 96 at its connection with pin 95 is a block 100 which may be clamped to both the rod 96 and pin 95 by means of suitable screws. Bi-metallic strips 101, 102, 103 and 104 are attached 75 to block 100 and extend upwardly therefrom.

Strips 101 and 102, which are nearest to rod 96, continue upward above it and are clamped between adjusting nuts 105 on a threaded rod 106, which passes through the top of tube 94. At a point opposite the upper end of strip 104, spacer blocks 107 are soldered to 103, 102 and 101 respectively, on one side only, so that 104 is free to slide relatively to the block on 103, 103 is similarly free at this point to slide relatively to 102 and so on. A clip 108 passes around all the bi-metallic strips 10 at this point as shown, and serves to keep them in slideable contact. In this way the forces at this point tending to bend the strips in either direction are accumulated and transmitted to the block 100 without lost motion or friction. A 15 similar arrangement of spacer blocks 107 and clip 108 is provided for the elements 103, 102 and 101 at the point opposite the upper end of strip 103. At the upper end of strips 101 and 102 but one spacer block 107 is required, soldered to either 101 20 or 102 and free to slide on the other. The adjusting nuts 105 here take the place of clip 108. 25

In this way the entire thermostatic element may be made of such shape that it will approximate a constant strength beam and will respond with maximum force to changes in temperature. In the example shown the material having a higher expansion coefficient is located on the side farthest from rod 96.

One side of sleeve 94 is cut away as shown at 30 109 to allow free access of air to the bi-metallic elements 101, 102, 103 and 104. Rod 96 extends upwardly from block 90 almost to the end of the longest bi-metallic elements in order to provide a counterweight for the lower portion that extends 35 into tube 88. It is desirable to have diaphragm 97 as close to the center of the hinge pin 95 as possible for this diaphragm must absorb a small amount of lateral distortion due to oscillation of the rod 96 about the pin 95, and the shorter this 40 distance, the less strain on the diaphragm.

By referring again to Figure 1 it will be seen that a second T connection 110 leads from the gas standpipe or main 36 to the inlet of the main valve 60, by means of conduit 111. A conduit 112 45 leads from the outlet of valve 60 to a burner 113, which may be of the conventional Bunsen type, and which is mounted on a suitable bracket 114 within a suitable metal shield or chimney 115. Chimney 115 is provided with a number of holes, 50 as indicated, below burner 113, to allow access of air for combustion. Holes may be provided in the base 11 directly below the chimney 115 and the holes in the chimney omitted in cases where the heater is to be used over a grated floor, as by 55 this means circulation of the surrounding air is provided by the formation of convection currents which aid in evenly distributing the heat.

It has been found that the ordinary Meeker type burner is preferable to use as the main source of heat. Any equivalent burner which is not seriously affected by changes in air-fuel ratio may be used. It is desirable that the initial adjustment of the burner be made for a lean mix so that, should the oxygen concentration in the compartment become somewhat depleted, essentially complete combustion can still be obtained.

As stated above, conduit 83 leads from the top of chamber 82 of the main valve 60 to a pilot 70 burner 116, which is mounted within chimney 115 and slightly below the top of the sleeve of main burner 113. The tip of pilot burner 116 may be of any desired shape but it has been found that a rather narrow slot with its edges somewhat 75

lower than the end of the pilot burner gives very good results.

The pilot burner 116 is preferably enclosed by means of a small covered sleeve or shield 117 attached to the inside of chimney 115 as shown. A hole approximately opposite the top of main burner 113 is provided through this shield to allow gas from the main burner to reach the flame of the pilot burner and become ignited therefrom. It will be noted that an opening is cut in chimney 115 immediately above the pilot burner 116 to allow the bi-metallic element 48 of the safety shut-off valve 37 to project therethrough and be exposed to the heat rising from the pilot burner. Shield 117 also serves to protect this bi-metallic toggle member from excessive radiation from the flame of the main burner 113.

An auxiliary perforated shield 118 outside of main shield 138 is provided around the thermostatically operated pilot valve mechanism described above, to prevent its damage or derangement from handling or transportation. The perforations of this shield should be such that free access of air is allowed to the thermally responsive element at all times. The combination of shields 130, 115 and 118 prevent drafts from blowing out the two burners, protect the burners and control equipment from mechanical damage, protect the cargo immediately surrounding the heater unit from excessive radiant heat, and protect the thermally responsive control elements from radiation from the main burner, which otherwise would cause it to function without relation to the temperature of the air in the compartment.

In operation, the valve 32 at the top of the storage tank or bottle 29 is opened, allowing gas to flow through conduit 33 to the pressure reducing valve 34. This may be adjusted to reduce the gas pressure to five to ten pounds per square inch by adjusting the handle 134 until the desired reduced pressure is indicated on the gauge 35. The handle 55 of the bi-metallic toggle mechanism on safety valve 37 is then moved to straighten out the toggle as described above, and allow valve member 39 to open under the impulse of its internal spring 40. This allows gas to flow into conduits 59 and 111, thence into the interior of tube 88 and to the inlet of main valve 60 respectively.

Assuming that the temperature of the atmosphere in which the apparatus is located is below that which it is desired to maintain, the bi-metallic elements 101, 102, 103 and 104 will have bent to cause the rod 96 to move in such manner that orifice 86 will be closed by the pilot valve member 99, and orifice 87 will be open. This condition will allow gas from conduit 59 to pass into tube 88, where it is prevented from escaping by diaphragm 97, through orifice 87 and conduit 25 to the lower cavity of the diaphragm of main valve 60. From this chamber a small stream of the gas will flow through passage 76, past needle valve 74 and through passage 80 into the chamber 82. From here it will flow through conduit 83 to the pilot burner 116, where it may be lighted by a match or other source of flame.

The gas which may be present in the space above diaphragm 71 of the main valve 60, will leak out through passage 77, past needle valve 75 and passage 81 to the chamber 82 which is at practically atmospheric pressure. This will allow the excess pressure of the gas below diaphragm 71 to urge the diaphragm upwardly, thus lifting

valve 63 from its seat 62 and allowing gas to pass through valve 60 and conduit 112 to the main burner 113. As the pilot burner 116 has already been ignited, the gas from the main burner 113 will be ignited therefrom, and will continue to burn as long as the temperature in the compartment is below that for which the bimetallic elements 101 to 104, have been adjusted. This adjustment may readily be secured by means of nuts 105 at the upper end of the elements.

It will be noted that the gas supply to the pilot burner 116 is uninterrupted by this action of the thermostatic pilot valve control mechanism, as gas flow exists through either orifice 86 or 87 and consequently needle valves 74 or 75 at all times. The heat from the pilot burner 116 maintains the bi-metallic toggle 48 of safety valve 37 concaved inwardly so that valve 39 remains open. Should the pilot flame become extinguished from any cause, the toggle element 48 will bend to its opposite position as shown in Figure 3, thereby shutting off the gas.

It will be apparent that the orifices 86 and 87 are of appreciable area, and that when either is covered by the valve member 99, a force approximately equivalent to the pressure in the tube 88 over this area holds the valve member 99 firmly seated. When the temperature in the storage compartment tends to cause a reversal of the position of valve element 89 by bending the thermostatic elements 101 to 104, sufficient work must be stored in the deflection of members 96 and 101 to 104, to overcome this force. When sufficient work is thus stored, rod 96 is quickly and positively moved to its opposite position where it remains until the action is reversed.

It will be apparent that the construction of the main valve 60 may be varied from that just described; for example, one of the operations of diaphragm 71 could be performed by a spring arranged to either open or close the valve 63. This would mean a construction in which but one orifice would need to be controlled by the thermostatic valve mechanism, and particularly the pilot valve member 99. An advantage to this type of construction would be that such a control mechanism could be arranged that the soft pilot valve member 99 was only in contact with its single orifice during such period as the gas supply was to flow through the main valve 60. This would relieve the wear on pilot valve member 99 and permit it to remain in good condition for a long time. Furthermore, there would be no requirement of storing work for both the opening and closing actions of the thermostatic pilot valve mechanism, thus allowing closer adjustment of temperature control. Many modifications of the valve seat 62 and valve disc 63 of valve 60 could also be made, in the interest of simplicity and cheapness.

Referring now to Figures 6, 7 and 8 which show an alternative form of the bi-metallic elements previously designated 101 to 104 of the thermostatic pilot valve mechanism. The tube 88 of Figure 8 is of substantially the same construction as that shown in Figure 5, except that it can be made considerably shorter. The flanges 91 and 92 are also as previously explained. A similar diaphragm 97 may be used to seal off the chamber within tube 88 from gas leakage. The rod 96 is arranged to oscillate about a pin or spindle 119 whose axis is at right angles to the axis of rod 96, and which passes through flange 92 as shown in Figure 8. A bracket 120 is attached to one side of flange 92 as shown in Fig-
